ROWING EXERCISER

Charles R. Margolies, Oreland, Pa., assignor to Snyder Manufacturing Company, Philadelphia, Pa., a corporation of Pennsylvania

Filed Sept. 16, 1969, Ser. No. 19,158

Term of patent 7 years

Int. Cl. D21—03

U.S. Cl. D34—5

FIG. 1.

FIG. 2.

FIG. 3.

FIG.4.

FIG.5.

FIG.6.

FIG. 1 is a top plan view of a rowing exerciser showing my new design;

FIG. 2 is a side elevational view illustrating the rowing exerciser in an inactive position;

FIG. 3 is an inverted plan view thereof;

FIG. 4 is a front elevational view thereof;

FIG. 5 is a rear elevational view thereof; and

FIG. 6 is a view similar to FIG. 2 illustrating the rowing exerciser in one of its active positions.

I claim:

The ornamental design for a rowing exerciser, substantially as shown and described.
